UNITED STATES PATENT OFFICE.

A. E. McGAUGHEY AND S. N. McGAUGHEY, OF WASTEDO, MINNESOTA.

IMPROVEMENT IN STEAM-PLOWS.

Specification forming part of Letters Patent No. 26,279, dated November 29, 1859.

To all whom it may concern:

Be it known that we, A. E. McGAUGHEY and S. N. McGAUGHEY, of Wastedo, in the county of Goodhue and State of Minnesota, have invented a new and Improved Steam-Plow; and we do hereby declare that the following is a full, clear, and exact description of the same, reference being had to the annexed drawings, making a part of this specification, in which—

Figure 1 is a side sectional view of our invention, taken in the line $x x$, Fig. 3. Fig. 2 is a back view of the same. Fig. 3 is a horizontal section of the same, taken in the line $x' x'$, Fig. 1.

Similar letters of reference indicate corresponding parts in the several figures.

This invention consists in the employment or use of a series of intermittently rotating and oscillating plows and oscillating or vibrating harrows so arranged as to operate in a transverse direction with the movement of the machine, substantially as hereinafter described, whereby several advantages are obtained over all previous arrangements of plows that have passed under our observation.

To enable those skilled in the art to fully understand and construct our invention, we will proceed to describe it.

A represents the frame of the machine, which may be of wood and constructed in any proper way to support the working parts. The front end of the frame A is supported by a caster-wheel, B, and the back part is supported by wheels C C, one at each side of the frame.

D is a boiler, of cylindrical form, which is suspended in the frame A from a hollow shaft, E, by means of bars a. The boiler D is so balanced as to have a tendency to remain in a horizontal position, the shaft E being fitted loosely in its bearings b.

F is a tube which communicates with the hollow shaft E and with the lower part of the boiler D, and G is a tube which also communicates with said tube and the upper part of the boiler. A stop is placed in the shaft E, between the two tubes F G, and water is forced into one end of shaft E and through the tube F into the boiler to supply the same, steam passing through the tube G into the shaft E and out from one end into proper tubes, (not represented,) by which it is conveyed into steam-cylinders H H, placed one at each side of the boiler and provided with

pistons, the rods J of which are connected by rods K to the cranks c of a driving-shaft, L.

The driving-shaft L has a pinion, d, on it, and this pinion gears into a wheel, M, on a shaft, N, immediately above it, the latter having a crank, e, on each end, the two cranks being placed in reverse positions and connected by rods f f to levers O O, which are placed one at each side of the frame A, and have each a connecting-rod, P, attached to its lower end, the back ends of said rods being connected to arms P' P', which are attached to vertical shafts Q Q in a sash, R, a shaft, Q, being near each end of said sash R. The sash R is simply a frame fitted between uprights g g at the back part of frame A, and allowed to slide up and down between the uprights, the sash being adjusted by a screw-rod, h, as shown clearly in Fig. 2. The lower ends of the shafts Q Q pass through bars i, the latter being secured to the shafts. The bars i extend across the lower beam of the sash R, and their front ends are each connected by rods j to similar bars, i' i', which are placed on shafts Q' Q' in the sash R. The back parts of the bars i i' extend downward and form the back bearings for shafts k, the front ends of which pass through the front parts of the bars i i', which also extend downward and form bearings for the front parts of the shaft, as shown clearly in Fig. 1.

On the front end of each shaft k a hub, l, is placed. To these hubs l three radial arms, m, are attached, and to the end of each arm a plow, S, is secured. These plows are of the usual form, such as are used for turning the sod or earth, each plow being provided with a mold-board and landside. The inner side of each hub l is notched, so as to form ratchet-tooth projections, as shown clearly in Fig. 3.

On the back part of each shaft k a pinion, u, is placed loosely, and to the back side of the lower bar of the sash R semicircular toothed racks T are secured, and into which the pinions n gear, a rack, T, being over each pinion. On each shaft k, adjoining the pinions n, a hub, o, is secured permanently. The inner sides of the pinions n are notched similar to the back sides of the hubs l, so as to form ratchet-tooth projections. The teeth of the pinions n have a reverse position to those of the hubs l, as shown clearly in Fig. 1.

On each shaft k a spiral spring, p , is placed, each spring being between two slides, qq , placed on its shaft k , which slides have rods r s attached, the rods s passing through the hubs o and bearing against the faces or toothed sides of the pinions n , and the rods r passing through the front vertical portions of the bars $i' i'$ and bearing against the toothed faces of the hubs l . (See Fig. 1.)

On the shaft N , at one end, a pulley, t , is placed, around which a belt, u , passes, said belt also passing around a pulley, v , on a shaft, w , in the frame A , which shaft has a pinion, a^x , on it, that gears into a toothed wheel, b^x , attached to and concentric with one of the wheels C . If necessary or desirable, both wheels C C may be thus connected with the shaft N .

The operation of the machine is as follows: The machine is propelled, it will be seen, by the application of power from the cylinders H , through the medium of the connecting-rods K , cranks e , gearing d M , belt u , and gearing a^x b^x . As the machine moves along, the bars $i' i'$, and consequently the shafts k and plows S , oscillate or move in the arcs of circles and transversely with the plane of the movement of the machine. This movement of the shafts k is produced by the cranks e , levers O O , connecting-rods P , arms P' , shafts Q Q' , and the bars $i' i'$, connected by the rods j .

Besides this movement of the plows S another one is given them by the pinions n and rack T . This latter movement, which is a rotating one, permits of the return motion of the plows after forming the furrow during their direct movement. The plows of two of the shafts k turn a furrow while moving from right to left, and the other two while moving in an opposite direction. When the plows S are at work, or during the movement in which the

furrows are formed, the plows are retained in proper position by the rods r , against which the teeth on the hubs l catch; and during the return or opposite movement of the shafts k the plows rotate out of the ground—that is to say, the ones that made the previous furrows—and the succeeding plow is brought in proper position for work, this latter movement being produced by the pinions n and racks T , the rods s catching into the pinions n and connecting the latter with the shafts k . The plows are made to pass a greater or less depth into the earth by adjusting the sash R .

To the back end of each bar $i' i'$ an arm, U , is attached. These arms are provided with rakes or harrows V , as shown clearly in Fig. 1. It will be seen that they have the same movement as the plows, and consequently smooth and level the work performed by them.

The boiler, in consequence of being suspended in the frame as shown, retains itself in a horizontal position by its own gravity.

Having thus described our invention, what we claim as new, and desire to secure by Letters Patent, is—

1. The plows S , attached to radial arms m or oscillating shafts k , and arranged with the pinions n , rack T , ratchet-toothed hubs l , and stop-rods r s , to operate substantially as and for the purpose set forth.

2. In connection with the plows S , arranged and operated as described, the rakes or harrows V , attached to the bars $i' i'$, for the purpose specified.

ALBERT E. McGAUGHEY.
SAMUEL N. McGAUGHEY.
